NAAMLOOZE VENNOOTSCHAP "KAMATEC," OF AMSTERDAM, NETHERLANDS

APPARATUS FOR SORTING PUNCHED CARDS WITH THE HELP OF FEELER PINS

Application filed July 24, 1928, Serial No. 295,005, and in the Netherlands August 10, 1927.

This invention relates to apparatus for sorting punched cards with the help of feeler pins, by means of which the cards are carried from the place of analyzing to the sorting-boxes. The object of such apparatus is to collect all cards, in which in a certain column the hole has been punched, which corresponds to a certain number.

Several systems are already known in which both electrically and mechanically the result of the feeling operation is transferred by means of the feeler pins to the movement of the deflectors which deflect the cards from their path to the sorting-boxes. The mechanical transfer of the feeling operation has the advantage of a much greater security of the operation so that consequently mistakes resulting from paper insulation or an imperfect operation of the relays are avoided. Although the electrical transfer necessitates the use of a continuous current, which is another drawback, it has, however, the great advantage of allowing a quicker operation, i. e. greater speed and consequently the treatment of a greater number of cards per time unit, as the card has not to discontinue its movement for the feeling operation to take place. Without the interruption, which hitherto was necessary in the mechanical transfer, the card can be guided from the magazine through the feeler apparatus to the conveyance apparatus.

According to the invention the transport of the card from the magazine through the feeler apparatus to the conveyance apparatus can also take place without interruption, when using the mechanical feeling operation, so that here besides the advantage of greater security of operation the advantage of great speed is obtained, whilst also by means of a considerable restriction of the movable parts the safety of working is increased and the apparatus becomes almost noiseless.

In the drawings a constructional example of the apparatus according to the invention is illustrated.

In these drawings:

Figure 1 is a diagrammatic front elevation of the apparatus,

Figure 2 a view of the chain movement,

Figure 3 a section of the feeler roller,

Figure 4 a longitudinal section of the feeler roller according to the line IV—IV in Figure 3,

Figure 5 a view of the collar transfer,

Figure 6 a diagram of the transfer of the collar movement to the locking apparatus,

Figure 7 a plan view according to Figure 6,

Figure 8 a diagram for the transfer of the movement on the adjustment of the deflectors for the cards,

Figure 9 the toothed wheels for the coupling of the shaft of the feeler roller with the transport rollers,

Figure 10 a plan view according to Figure 9.

In a plate 1 of the frame, on which the card-magazine 2 is placed, a series of parallel slots 3 are provided through which during the rotation the feed-knives, (not shown) divided according to the slots 3, can move. These knives push each time the lowermost card so much in a forward direction that the latter comes between the rotating transport-rollers 7, which guide the card between the feeler roller 8 and the guiding plate 9, which is provided with slots 9a. In this position the card is within reach of the rotating press rollers 10, which guide it without stoppage to the series of transport rollers 11, which are actuated by means of an endless belt 12, which is mounted on the feeler roller, so that the card is guided with a uniform speed past the several sorting-boxes 61, in which with the help of the deflectors 36, in a manner which will be described later on, the cards are placed in accordance with the precise position of the hole in the card.

By way of explanation it is pointed out that the apparatus must be adapted to sort according to twelve grades, as not only a sorting must be possible according to the numbers 0-9, but also according to the twelve months of the year. In connection herewith there are twelve sorting-boxes 61, and each series of feeler pins consists of twelve pins.

The feeler roller 8 (Figure 3) consists of a cylinder, comprising a number of rods 44, lying in longitudinal direction, which by

means of angle-pieces 46 are connected with the end plates 45 of the feeler roller. Between the rods 44 the feeler pins 13 are arranged, which are pressed outward by means 5 of springs. In consequence of the fact that the speed of the surface of the feeler roller determines also the speed of the movement of the cards, it is possible that, as is the case in the illustrated constructural example, the 10 developed surface of the feeler roller represents a plurality of the dimensions of a card in the direction of its movement so that in the same proportion an equal number of twelve feeler pins must be present in the 15 feeler roller. Between two successive series, however, a rod 44 of greater dimensions, is arranged, in accordance with the distance between two cards on their way to the sorting-boxes. According to the constructional 20 example three series of feeler pins are provided, so that also three rods 44 of greater dimension are illustrated. It has been shown that it was unnecessary to provide for as many rods 44 as there are feeler pins.

25 The feeler pins themselves are arranged in radial direction (Figure 4) on a feeler disc 39, which is affixed to the outer ring of a ball bearing 38 in the feeler roller, and of which the inner ring is connected with a nut 37, screwed on a threaded rod 41. The nut 37 is moreover provided with a bored hole for a guiding rod 40, which is fixed to both the end surfaces of the feeler roller.

In view of the fact that the rotation of the 25 nut 37 is prevented by the guiding rod 40, the rotation of the threaded rod 41 by means of a handle 42 projecting outside the apparatus can cause the forward pushing of the nut 37 with the ball bearing 38 and the feeler disc 39 in axial direction for the adjustment of the feeler disc to the column for which the feeling operation is desired. The thread on the rod 41 can be chosen in such a way that one rotation of the handle 42 corresponds to 40 a displacement of the feeler disc over the distance between one column and the next. When the feeler roller rotates, the feeler disc runs along with the outer ring of the ball bearing, whilst the inner ring stands still.

50 A chain wheel 47 is furthermore attached to the feeler roller 8 (Figure 2) which consequently rotates together with the feeler roller and by means of which an endless chain 49, which is mounted on the disc 47 and a second disc 48 (Figure 1), is driven. Arms 50 are attached to this chain 49 at intervals corresponding to the mutual distance of the cards during the movement along the feeler roller, so that an arm 50 accompanies every card. 55 At the fixing point on the chain these arms are provided with springs 50a, which press the arms permanently outwards, i. e. away from the chain. At its extremity each arm is provided with a pin 51 perpendicular to the 60 arm. These pins therefore are retained in

outwardly projected positions as long as no obstacle is in their path. Such an obstacle, however, is embodied in a guiding plate 28, arranged in the proximity of the chain disc 47, and of such shape that the pins 51 are 70 always guided through an inclined slot 28a, provided between the guiding plate 28 and the starting points of the twelve guiding paths 29 (Figure 2), provided along the sorting boxes. As long as this slot is unobstructed the pins 51 will move freely through it and will be pressed again outwards, when leaving it. As will appear later on, the pins 51 are caused to move along one of the guiding paths 29.

80 Above the guiding plate 9 a vertically positioned toothed plate 14 is arranged, which is rotatable round a shaft 15. The plate 9 contains as many slots as there are columns on the card, through which slots the feeler pins 13 pass. The plate 14 is provided with as many teeth, which are arranged right above the slots of the plate 9. As it is desirable, namely to prevent damage to the holes in the cards, that the feeler pins do not project too

90 far outwards, the teeth of the plate 14 must be arranged as near as possible to the plate 9. However, in order to make it possible to move the feeler pins freely, when there is no card in the apparatus, the plate 14 must be raised in such a case. This takes place by means of the arms 54, which clutch the shaft 15 of the plate 14 and which with the other

100 end are each connected with jointed toothed plates 53, provided on each side of the feeler roller. The teeth of these plates engage with the teeth of plates 52 attached to the frame and between these two sets of teeth the card is guided before reaching and after leaving the feeler roller. As soon as a card leaves the magazine and passes between the first set of toothed plates 52, 53, the plate 53 is raised,

105 so that the fork of the arm 54 connected therewith lowers the plate 14 and brings it, i. e. its teeth, within reach of the feeler pins. When the card has passed the feeler roller it performs the same operation with the help of the second set of toothed plates 52, 53. Before a card has also passed this set of plates 52, 53

110 a next card has already come between the first set 52, 53, so that only when there is no card in the apparatus above the feeler roller are both sets 52, 53 out of operation and the plate 14 is raised.

115 The plate 14 is arranged between two arms 16 (Figure 4), which are attached to an arm attached to a shaft 17, so that therefore the plate 14 can move freely up and downwards, whilst when a feeler pin strikes against the plate 14, it will rotate round a shaft 15, whereby it strikes against one of the arms 16 and in this way slightly rotates the shaft 17.

120 The rotation of the shaft is used for the adjustment of the movement for the card deflectors.

The shaft 17 is provided with an arm 18 connected by a rod 19 with an angle-lever 20, rotatable round shaft 22. The extremity of this angle-lever near to the toothed wheel 47 is provided with a bow-shaped plate 21 (Figure 5), which at the rotation of the shaft 17, as a result of the rotation of plate 14 round shaft 15, is moved in the direction of a series of twelve pins 23, arranged in a circular arc.

10 A disc 24, to which for each series of feeler pins 13 (in the example therefore three) a block 25 is secured by means of a blade-spring 25a, rotates between the pins 23 and the curved piece 21 along with the shaft of the feeler roller 8. The blocks are so positioned that during the rotation of the disc 24 a block is disposed opposite the first of the group of pins 23 on the moment that the first feeler pin of the corresponding series moves 15 past the plate 14 and the blocks are movable through openings 25b in the disc 24. On the circumference of the same disc and in the moving direction a pin 26 is, moreover, arranged behind each block 25.

20 25 Each pin 23 (Figures 6 and 7) is connected with a rotatable arm 27, which during the pressing-down of the corresponding pin 23 is rotated in such manner that its extremity is pushed in the manner of a lock or guiding arm in the slot between the guiding plate 28 and the twelve guiding paths 29 (Figure 2) as is illustrated in Figure 7 for one of the arms 27. Each pin 23 is, furthermore, provided with an offset piece 30 with a slanting curved extremity 31, which at the pressing-down of the pin 23 comes into the path of the pins 26.

25 30 In every guiding path 29 (Figure 8) there is arranged almost at the extremity an arm 33 attached to a vertical shaft 32. To the other extremity of the shaft 32 an arm 34 is connected, which is attached to the frame with a spring, which arm is coupled by means of a string or cable, such as a Bowden wire, 35 with a deflector 36 of the corresponding sorting-box 61.

35 40 For enabling the use of the apparatus the disc 39 with the feeler pins must first be adjusted with the help of the handle 42 (Figure 4) to the column, on which the feeling operation (therefore also the sorting) must take place. In order to make it possible that during this displacement the feeler pins, which now move in the longitudinal direction of the feeler roller, can move freely and clear of the guiding plate 9, which is provided with slots, this plate is connected with a lever 56 (Figures 1 and 3) which is provided with a roller 55, which in the position of operation rests in a recess of a disc 57, connected with the handle 42. As soon as the handle 42 is rotated the edge of disc 57 raises the roller 55 of the lever 56 so that the guiding plate 9 is rotated in such manner that the feeler pins can freely pass to the position of the next

45 column which is reached after a full rotation of the handle 42, in which position the roller 55 of lever 56 comes to rest again in the recess of the disc 57 and therefore the guiding plate 9 will be also again in the position of operation. This arrangement renders it possible to bring the disc with the feeler pins into another position even when the feeler roller is rotating.

50 55 During the passing of the card along the feeler roller a series of feeler pins run also in such way that the first feeler pin comes into contact with the card on the place in which the first hole of the column may be made, the second feeler pin with the place for the second hole of the column, and so on. In case there is a hole in the card on the fifth place the fifth feeler pin will project through the hole in the card (in contradistinction to all the other feeler pins which are withheld by means of the card) and will come into contact with the plate 14, i. e. with its tooth, that corresponds to the feeler column. This plate 14 having been brought into its lowest position by means of the arms 54, owing to the presence of the card, is carried along for a short space by the feeler pin in the direction of rotation, which owing to the movement of the shaft 17 causes also a rotation of the shaft 22 through the members 18 and 19. The resulting movement of the curved plate 21 in the direction of the pins 23 causes the block 25, associated with the set of feeler pins 13 operating on the card passing through the machine, to be depressed at the moment it is opposite the fifth pin 23. When the fifth feeler pin 13 has passed the plate 14 the latter returns to normal position together with lever 22 and the blade-spring 25a, to which the block 25 is affixed, brings it out of contact with the following pins 23. The pushing-in of the fifth pin 23 causes also the fifth rotatable arm 27 to be pushed as a guiding arm into the slot between the guiding surface 28 and the extremity of the guiding paths 9 just above the upper edge of the fifth guiding path 29. Guiding arm 27 and pin 23 with the curved downward extremity 31 of the lengthening bar 30 connected thereto remain in this position so that when the first oncoming pin 51, which with regard to time just runs behind the block 25, passes through the slot, the arm 27 brought therein forces the pin to enter into the fifth guiding path and to continue therein the now following part 100 105 of its path. When the block 25 has passed the last pin 23, the pin 26 belonging to this block 25 pulls the pin 23 back owing to its movement along the sloping part of the offset piece 30, by which also the arm 27 in the slot 110 115 is withdrawn.

115 120 125 130 As has been pointed out before, the pin 51 moves through the guiding path together with the card, which is guided along the sorting-boxes 61. A moment before pin 51

reaches the extremity of the guiding path, into which it is guided (hence in this example the fifth), the pin strikes against the arm 33, mounted therein, by which the shaft 32 (Figure 8) is rotated. This causes a pushing movement in the cable 35 connected with the corresponding (fifth) deflector 36. Hence the deflector is rotated so far that it comes in the path of the cards, formed by the transport-roller 11 and contra-rollers, so that by means of the rotated deflector the oncoming card does not reach the next transport-roller, but is guided downwards and drops into the desired (fifth) sorting-box 61, whilst immediately thereafter the deflector returns owing to the spring of the arm 34, so that the next card, which may be destined for a more remote sorting-box, can continue its course, till it reaches the deflector of this sorting-box.

It is desirable not to make the guiding paths 29 longer than necessary, i. e. to let them finish just beyond the place of the arms 33. This has namely the advantage that the next following pin 51, which moves through it, is able to move so much outwards till it strikes against the under-edge of the following guiding path. At the points where this path ends, the outside movement then follows against the next guiding path and so on.

The result of this is that the pins instead of suddenly accomplishing the complete outside deviation at once, which would be especially considerable for the first sorting-boxes, deviate by degrees and therefore gradually.

It is, moreover, unnecessary to continue the guiding paths 29 to the corresponding sorting-box 61. When the chain discs 47 and 48 have smaller diameters than the feeler roller, as is illustrated in the drawing, the chain 49 moves slower in the same degree and the guiding paths can be shorter in the same proportion.

In order to more quickly obtain the adjustment of the feeler disc 39 (Figure 4) on the desired feeler column than by the accomplishment of as many rotations of the handle 42, a coupling of the threaded rod 41 with the shaft of the undermost transport-roller 7 can be effected in the manner as illustrated in Figures 9 and 10. To the disc 57, connected with the handle 42, a toothed wheel is attached which can be coupled with a toothed wheel 59, which is mounted on the shaft of the transport-roller 7 and is movable. This toothed wheel 59 is in continuous engagement with a toothed wheel 60, coupled therewith by means of a cross-bar which through rotation of this cross-bar can be brought into engagement with the toothed wheel 58. When therefore the toothed wheel 59 is shifted, direct coupling of the toothed wheels 58 and 59 is obtained so that the transport-roller 7 brings the threaded rod 41 into rotation till the desired position of the feeder disc is ob-

tained. For the movement of the threaded rod 41 in a contrary direction the toothed wheel 60 is rotated out of the illustrated position till it engages with the toothed wheel 58 so that the transport-roller 7 now rotates the threaded rod 41 in a contrary direction over the toothed wheels 59, 60, 58. During the action of the machine the adjustment of the feeler disc is effected by one of the two couplings.

Having now described my invention, what I claim as new and desire to secure by Letters Patent is:—

1. Apparatus for sorting punched cards including a rotating feeler roller, resiliently projected feeler pins carried by said roller, a movable plate adapted to be actuated by said pins, sorting boxes, deflectors associated with the sorting boxes, and means for transmitting movement of said plate to any one of said deflectors for actuating the latter, said plate being movable by the pins in a direction perpendicular to the axis of the latter.

2. Apparatus for sorting punched cards including a rotating feeler roller, resiliently projected feeler pins carried by said roller, a movable plate adapted to be actuated by said pins, sorting boxes, deflectors associated with the sorting boxes, and means for connecting said plate with any one of said deflectors for actuating the latter, said plate being movable by the pins in a direction perpendicular to the axis of the latter, said means connecting the plate with the deflectors including a series of guide paths corresponding in number to the number of sorting boxes, a member movable in synchronism with a punched card adapted to enter said guiding paths, and means adapted to direct said member into a path associated with the sorting boxes corresponding to the punched card passing through the apparatus.

3. Apparatus for sorting punched cards including a rotating feeler roller, resiliently projected feeler pins carried by said roller, a movable plate adapted to be actuated by said pins, sorting boxes, deflectors associated with the sorting boxes, and means for connecting said plate with any one of said deflectors for actuating the latter, said plate being movable by the pins in a direction perpendicular to the axis of the latter, said means connecting the plate with the deflectors including a series of guide paths corresponding in number to the number of sorting boxes, a member movable in synchronism with a punched card adapted to enter said guiding paths, and means adapted to direct said member into a path associated with the sorting boxes corresponding to the punched card passing through the apparatus, and means located in each path and engageable by said member for operating the associated deflector.

4. Apparatus for sorting punched cards including a rotating feeler roller, a resiliently projected feeler pins carried by said roller, a movable plate adapted to be actuated by said pins, sorting boxes, deflectors associated with the sorting boxes, and means for connecting said plate with any one of said deflectors for actuating the latter, said plate being movable by the pins in a direction perpendicular to the axis of the latter, said means connecting the plate with the deflectors including a series of guide paths corresponding to and associated with the sorting boxes, a member movable in synchronism with punched card adapted to enter said guide paths, means for directing said member into the proper guide paths, selectively operable members for actuating the directing means, a member rotated in synchronism with the feeler roller, and a member carried by the rotatable member operable coincidentally with movement of said plate to engage and operate the selectively operable members.
5. An apparatus as claimed in claim 4, characterized by the provision of means on the rotatable member for resetting the selectively operable members.
6. An apparatus as claimed in claim 2, characterized by the provision of means for guiding the member movable in synchronism with a punched card in advance of its entry into one of the guide paths.
7. An apparatus as claimed in claim 4, characterized in that said paths terminate in proximity to the sorting boxes associated therewith.
8. An apparatus as claimed in claim 1, characterized by the provision of means for moving said plate into the path of the feeler pins.
9. An apparatus as claimed in claim 1, characterized by the provision of means for moving said plate into the path of the pins, said means being card-operated.
10. An apparatus as claimed in claim 1, characterized by the provision of means for moving the pins axially of the roller.
11. An apparatus as claimed in claim 1, characterized by the provision of means for moving the pins axially of the roller, and means for indicating the displacement of said pins through a space corresponding with the distance between the perforations of a punched card.

In testimony whereof I have signed my name to this specification.

CORNELIS HENDRICUS STUIVENBERG.
